UNITED STATES PATENT OFFICE.

DOCTOR KENT EARLY, OF SALEM, VIRGINIA.

RAIL-FASTENING DEVICE.

1,413,462.

Specification of Letters Patent. Patented Apr. 18, 1922.

Application filed January 13, 1922. Serial No. 528,992.

To all whom it may concern:

Be it known that I, Doctor KENT EARLY, a citizen of the United States, residing at Salem, in the county of Roanoke and State 5 of Virginia, have invented new and useful Improvements in Rail-Fastening Devices, of which the following is a specification.

This invention relates to a rail fastener or tie plate and contemplates a device not 10 only simple in design and inexpensive to manufacture but one in which the rail will be rigidly anchored to the supporting tie and secured against spreading or creeping.

It relates in particular to a device of this 15 character in which the tendency of the tie plate to wear into and split the tie is eliminated.

The invention resides in the construction, arrangement and combination of elements 20 hereinafter set forth, more particularly pointed out in the appended claims and illustrated by the accompanying drawings, in which:—

Figure 1 is a view in perspective showing 25 a railroad tie having the improved tie plate secured thereto.

Figure 2 is a perspective view showing a tie adapted for use with my novel tie plate, the tie being shown as partly broken 30 away.

Figure 3 is a longitudinal section on the line 3—3, Figure 1.

Figure 4 is a perspective view of the fastener.

35 Referring to the drawings, a tie 1, of any suitable material, has resting on it metallic tie plates or fasteners 2 having posts 3 depending therefrom and formed integral therewith. Sockets 4 are formed in the upper surface of the tie 1 to receive the posts 3 of the fastener. The posts 3 are preferably rectangular in cross section and preferably have their sides, which extend at right angles to the length of the tie, longer than 40 their sides which extend transversely of the tie. Transverse passages 5 are formed in the tie, these passages intersecting the sockets 4, and similar transverse passages 5^a are formed in the longer dimensions of the posts

45 3, the latter passages 5^a being adapted to register with the passages 5 in the tie when the plates 2 are in position on the tie. Bolts 10 pass through passages 5 and 5^a and are secured from displacement therein by nuts

50 55 11. Each tie plate 2 has a depression 6 in

its upper face to receive the base flange 8 of a rail 7, and the sides of these depressions, by reason of their engagement with the edges of the base flanges 8 of the rail, serve to prevent lateral displacement of the 60 rails. The tie plates are formed with vertical holes 9 adjacent to the depression 6, one of said holes being located on each side of each depression, and spikes 10^a having heads 11^a for engagement with the base 65 flanges 8 of the rail 7 are driven through said holes 9 into the tie 1. The holes 9 in tie plate 2 are in staggered relation to one another and lie within the planes defined by the sides of posts 3 parallel to the length of the tie. 70

From the foregoing description it will be readily understood that any pressure exerted on the rails 7, tending to spread them apart, will be transmitted through the tie plate 2, and more particularly the posts thereof, to 75 the tie 1. The posts 3 being rectangular in cross section, with their broadest faces at right angles to the length of the tie, this thrust will be transmitted to a considerable cross sectional area of the tie and the danger 80 of the posts wearing into the tie will be avoided. Furthermore, with the wooden ties generally in use, the wood grain runs with the length of the tie and the device contemplated having its faces, for transmitting the thrust, at right angles to the grain of the wood, all tendency towards separating the grain and splitting the tie will be avoided. The tie plates are secured against displacement from the tie by means of the 85 bolts shown. These bolts also serve to clamp the wood fibers together and prevent splitting. The rails 7 rest in the grooves 6 and are secured therein by the spikes shown and thus rigidly fastened to the tie plate. 90 The spike holes, being within the planes defined by the sides of posts 3 in parallel relation to the length of the tie prevent any splitting caused by their insertion from extending beyond sockets 4. It will be understood that minor changes in detail may be made within the scope of the invention. 95

Having described the preferred embodiment of my invention what I claim is:—

1. A rail fastening device having in combination, a tie, a metallic tie plate resting thereon, rectangular posts depending from and integral with said tie plate, said rectangular posts having sides of broad area arranged transversely to the length of the 105 tie, and a rail having a base flange resting in a depression in the upper surface of the tie plate, the sides of the depression being engaged with the edges of the base flanges of the rail, and spikes having heads for engagement with the base flanges of the rail being driven through the tie plate into the tie, the holes in the tie plate being in staggered relation to one another and lie within the planes defined by the sides of the posts parallel to the length of the tie. 110

tie, sockets in said tie for said posts, securing means passing through the tie and the posts, said tie plate being adapted to receive a rail and means for securing the rail 5 to the tie plate.

2. A rail fastening device having in combination, a tie, a metallic tie plate resting thereon, rectangular posts depending from and integral with said tie plate, said posts 10 having their broadest sides arranged transversely to the length of the tie, sockets in said tie for said posts, securing means passing through the tie and the posts, said tie plate being provided with a groove adapted 15 to receive a rail, and means for securing said rail in said groove.

3. A rail fastening device having in combination, a tie, a metallic tie plate resting thereon, rectangular posts depending from 20 and integral with said tie plate, said posts having their broadest sides arranged transversely to the length of the tie, sockets in said tie for said posts, bolts passing through said tie and said posts, nuts on said bolts, 25 said tie plate being provided with a groove

adapted to receive a rail, and means for securing said rail to said tie plate.

4. A rail fastening device having in combination, a tie, a metallic tie plate resting thereon, rectangular posts depending from 30 and integral with said tie plate, said posts having their broadest sides arranged transversely to the length of the tie, sockets in said tie for said posts, securing means passing through said tie and said posts, said tie 35 plate being provided with a groove adapted to receive a rail, and means for securing said rail to said tie plate comprising holes in said tie plate, said holes lying within planes defined by the sides of the posts in 40 parallel relation to the length of the tie and spikes driven through said holes into said tie.

In testimony whereof I have hereunto set my hand in presence of two subscribing witnesses. 45

DOCTOR KENT EARLY.
